CLAIM

The ornamental design for a seat module, substantially as shown and described.

DESCRIPTION

FIG. 1 is a perspective view of a seat module showing my new design;

FIG. 2 is a top plan view of this seat;

FIG. 3 is an elevational view of the seat, looking from the left as viewed in FIG. 1, the view from the right as viewed in FIG. 1 being the same;

FIG. 4 is a bottom view of the seat; and

FIG. 5 is a front elevational view of the seat shown in FIG. 1, the rear elevational view being the same.

FIG. 1.

FIG. 2.

FIG. 3.

FIG. 4.

FIG. 5.
